UNITED STATES PATENT OFFICE.

WILLIAM E. AHERN, OF WORCESTER, MASSACHUSETTS, ASSIGNOR OF TWO-THIRDS TO
GEORGE M. BASSETT AND ONE-THIRD TO ARTHUR J. BASSETT, BOTH OF WORCESTER,
MASSACHUSETTS.

MULE-SPINNING MACHINE.

No. 867,332.

Specification of Letters Patent.

Patented Oct. 1, 1907.

Application filed January 2, 1907. Serial No. 350,416.

To all whom it may concern:

Be it known that I, WILLIAM E. AHERN, a citizen of the United States, residing at Worcester, in the county of Worcester and State of Massachusetts, have invented 5
a new and useful Improvement in Mule-Spinning Machines, of which the following is a specification, reference being made therein to the accompanying drawings.

This invention relates to a novel means or construction combined with the cop-builder mechanism of a spinning mule, or employed as an attachment thereto; the object of the invention being to prevent the yarn from throwing off at the nose or point of the bobbins when winding on the latter portion of the stretch, 10 especially when the bobbins are nearly filled. Also, to obviate the tendency of the yarn growing heavier in the strand as the bobbin becomes filled towards the top-end thereof, while maintaining the same or uniform delivery of roving at each time of action. I attain 15 these objects by a mechanism embodying the features of construction and combinations explained in the following detailed description and illustrated in the drawings; the particular subject matter claimed being definitely pointed out and expressed in the summary.

20 In the drawings, Figure 1 represents a sectional side elevation, including such parts of a mule spinning machine as will show the nature of my invention. Fig. 2 is a side view of the rear part of the cop-builder rail and improved nose-forming means. Fig. 3 is a plan 25 view of the parts embraced in Fig. 2; and Fig. 4 is a transverse section at the line X X on Fig. 3.

Referring to the drawings, A denotes the carriage, a the spindle and bobbin, B the roving delivering rolls; C and D the fallers carrying the faller-wires respectively 30 above and below the yarn. E indicates the faller-lock; F the faller-lock carrier or builder-arm; G the traveler-roll of said carrier; I the cop-builder-rail upon which said roll travels; J and J¹ the inclined supporters or builder-plates; K their connecting rod; and L the 35 regulating screw for shifting said builder-plates end- wise for elevating and depressing the rail I, which latter is gradually depressed as the bobbins are filled in the operation of the spinning mechanism. All of the 40 above indicated parts, excepting the builder rail I, are of usual well known construction, but are herein shown in a general way to represent the relation of the mechanisms and the manner in which the within described 45 invention is adapted to be employed therewith.

The operation and structure of such parts of a complete spinning machine as are not herein shown and particularly described, are well known and will be understood by those skilled in the art, in so far as respects the operation of the present invention.

In accordance with my invention, the rear end of the builder-rail I is provided with a movable wedge-shaped nose-forming element mounted thereon and adapted to be slidably adjusted endwise upon the rail, or automatically controlled in respect to its relative position; and which acting through the medium of the faller mechanism, governs the final windings of yarn at 55 the latter part of each stretch, as it is wound upon the bobbin, by effecting a peculiar regressive or ducking movement of the wind-guiding faller; thereby causing the finishing coils to be placed in such relation that the yarn will not throw off by the rapid rotation of the 60 bobbin, nor slacken and kink when the fallers are released preparatory to commencing the run-out for spinning of the succeeding stretch. This nose-forming element, as illustrated in the drawings, comprises an 65 endwise movable, forwardly tapered wedge or piece 70 3, about fourteen inches, more or less, in length and having a track surface upon its upper side disposed in continuation of the track surface of the builder-rail I, upon which the roll G of the faller-lock carrier F runs. The top of said adjustable nose-forming piece 75 is longitudinally inclined in a direction opposite to the inclination of the top surface of the builder-rail, and meets said rail surface with a comparatively thin edge at its end 2, so that the roll G will pass easily from the rail surface to the nose-former surface. 80

The rear end of the builder-rail is preferably made with an attached rearward extension 5, upon which the nose-former 3 is adjustably supported, and guided by intermeshing longitudinal groove and ribs 6 which prevent lateral displacement while permitting end- wise movement of the nose-former piece thereon. 85 The extension 5 may in some instances be an integral part of the builder-rail; but is preferably constructed as a separate piece, and attached to the end of the builder-rail, as shown, by screw-bolts 7 or equivalent 90 fastenings; since such separate construction facilitates the convenient and accurate formation thereon of the guiding ribs and grooves; and also renders it easy to apply the improved attachment to spinning-machines which are already in use, as well as to machines in 95 manufacture. The top of the extension piece is in alinement with the top of the builder-rail and the member 3 is seated upon the top of each so as to be movable endwise thereon. It can also be lifted off when desired. 100

The nose-former piece 3 is coupled to the movable builder-plate by a stud 9 that is fixed in the side of the nose-former piece, and which engages with a slotted upwardly projecting arm 10 that is firmly secured to a rearwardly extended portion 11 of said builder-plate J. 105 The arm 10 is pivotally adjustable on its attaching bolt

12, so that it can be set upright, or with either forward or rearward inclination; thereby enabling the nose-former 3 to assume positions relatively more or less forward or rearward in respect to the inclined portion of 5 said builder-plate upon which the ear or button 13 of the builder-rail I rests. The several latter named parts are supported and guided by the standard 14, as shown.

The top of the builder-rail I is preferably formed 10 with an extra downward inclination from a point *x* rearward in relation to the normal line of the central top of the rail; such inclination being in the proportion of about one quarter inch, more or less, to a length of sixteen inches. The point *x* is located at a position 15 corresponding to about two thirds or three fourths of the wind-up.

Movement of the two inclined builder-plates J and J¹, for gradually lowering the builder-rail I and carrying the winding-on up the bobbin, is effected by 20 means of the regulating screw L, the nut M on which is attached to the plate-connecting rod K in the usual manner.

The screw L is provided with the customary ratchet mechanism at P which is intermittently actuated, automatically, as heretofore practiced, or in any suitable manner.

In the operation, as the traveler-roll G runs along the builder-rail I, from its fore end to the point *i*, and thence to the point *x*, the faller C first guides the yarn 30 down the cone of the cop and then upward along the cone in the usual manner. Then as the roll travels along the rail rearward from the point *x* the extra incline of the rail gives a somewhat increased rise to the faller until the winding comes to the wood of the bobbin, and the traveler-roll runs onto the end of the oppositely inclined adjustable nose-former 3, which latter 35 imparts a "duck" or downward movement to the winder-guide faller C, thereby causing a downward wind of the yarn at the extreme point of the cone, or 40 the laying of downwardly wound coils over the later upwardly wound coils; thus finishing each wind-up with a downward instead of an upward wind upon the nose of the cop when the fallers are released. The advantages of this improved means and operation are, 45 that the coils at the latter end of the wind are held close and the yarn prevented from throwing off when near the top of the bobbin. The yarn being closely wound up, and so held, obviates the liability of an increase in weight of the strand when spinning on nearly 50 full bobbins. The secure holding of the coils at the end of the wind-up also serves to prevent kinking between the delivery-rolls and spindle points when the fallers are released.

By the endwise adjustment of the piece 3 the nose-forming action can be brought into effect at an earlier or later instant in the wind-up operation; and the nose-former can be located upon the rail I so as to come into action at a point where the bobbin is more or less filled. Said nose-former being automatically adjustable in connection with the means that controls the builder-rail, it is rendered increasingly effective as the winding-on approaches the top of the bobbins so that any desired degree of "duck" or regressive wind can be given near the final nosing as the bobbins become 65 filled.

The nose-former piece 3 may be provided with a plurality of holes 15, in either of which the stud 9 can be placed; and the extension on the builder-plate J may be made with a plurality of holes 16 for receiving the bolt 12, thus affording a wide range of adjustments. 70 When the slotted arm 10 is set at a rearward inclination the advance movement of the nose-former is proportionally accelerated with respect to the downward movement of the builder-rail, and when the arm is set at a forward inclination the advancing movement of 75 the nose-former is proportionally retarded with respect to the movement of the builder rail. The result of this is that the nose-winding "duck" movement of the faller C can be variously regulated to give greater or less increase of effect, as the winding-on of the yarn 80 approaches the top end of the bobbins, so as to conform to the requirements of spinning different kinds of yarns or stock, and the degrees of twist; or to take up the yarn more or less closely, so as to obviate kinking between the bobbins and rolls B, as the fallers are released. 85

I claim and desire to secure by Letters Patent—

1. In a mule spinning machine, the combination, with fallers, faller-lock mechanism, and cop builder-rail; of an adjustable nose-forming means disposed at the rear end 90 of the builder-rail and comprising a flatwise tapered wedge-shaped member overlying the top surface of the cop-builder-rail and longitudinally adjustable thereon to and from a position that corresponds to the final part of the wind-up, and means for effecting endwise adjustment of 95 said member to give later or earlier effect when coacting with the faller-lock carrier for imparting a final downward wind at the latter end of the winding-on action.

2. In mechanism of the class described, in combination with the faller mechanism, its carrier roll, the builder-rail, and inclined builder-plates supporting said builder-rail; an endwise movable nose-forming element comprising a forwardly tapered piece mounted on guide-ways in connection with the rear part of said builder-rail, and in continuation of the track surface thereof, and means in connection with one of the inclined builder-plates, for moving said nose-forming element endwise in relation to the builder-rail. 100

3. In a mule spinning machine, the combination, with the faller mechanism, and cop-builder-rail, of an attachable rear-end extension member having longitudinal guide-ways thereon, means for securing said member to the rear end of said builder-rail, an endwise movable forwardly tapered nose-former piece fitted on said guide-ways and extending along the top of the builder-rail, and engaging 110 means for automatically effecting endwise movement of said nose-former in conjunction with the means for depressing the builder-rail. 115

4. In a mule spinning machine, in combination with the fallers, faller-lock mechanism, builder-rail, inclined builder-plates, and plate regulating screw; a removable endwise-slidable inclined nose-former-piece arranged at the rear part of the builder-rail in alignment with the track surface thereof, a stud fixed in said nose-former piece, and a slotted arm carried by the builder-plate and engaging with 120 said stud, for the purposes set forth.

5. In mechanism of the class described, the combination, with the faller-lock carrier, builder-rail, and movable wedge-shaped builder-plate supporting said builder-rail; of a tapered endwise movable nose-former member mounted 130 on the builder-rail, an actuating arm carried by the builder-plate, and means connecting said arm and nose-former member, said arm being adjustable to forward or rearward inclination for varying the relative position and action of the nose-former member in respect to the builder-rail and 135 faller-lock-carrier.

6. In a mule spinning machine, in combination, a self-operating nose-former device carried upon the builder-rail and coacting with the traveler roll and faller mechanism, means for automatically regulating the fall of the builder- 140

rail, and means for automatically shifting said nose-former device forward upon the builder-rail, for increasingly modifying the wind of yarn at the nose of the bobbin, substantially as set forth.

5 7. In a mechanism for the purpose described, the combination of the builder-rail, the builder-plate having a rearward extension provided with a plurality of openings therein, a tapered nose-forming piece mounted for endwise movement upon said builder-rail, a projecting stud on said

movable piece, and a slotted arm engaging with said stud 10 and attached to said builder-plate extension by an adjustable connection.

Witness my hand this 29th day of December, 1906.
